UNITED STATES PATENT OFFICE.

WILLIAM B. FOSTER, OF UTICA, NEW YORK, ASSIGNOR TO FOSTER BROTHERS MANUFACTURING COMPANY, OF UTICA, NEW YORK, A CORPORATION.

ADJUSTABLE BED-HANGER CONSTRUCTION.

Application filed October 11, 1923. Serial No. 668,013.

To all whom it may concern:

Be it known that I, WILLIAM B. FOSTER, a citizen of the United States, and a resident of the city of Utica, in the county of Oneida and State of New York, have invented certain new and useful Improvements in Adjustable Bed-Hanger Construction; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to an adjustable bed-hanger construction.

The purpose of my invention is to provide an adjustable bed hanger of simple and durable construction and one capable of being readily used in a variety of places.

A further purpose is to provide an article of the class described which will be very effective and strong; but is composed of a minimum number of new parts by reason of utilizing in new manner the usual angle iron edge bar of the bed bottom.

A still further object is to combine the few strong simple parts with the angle iron side bar of a bed bottom so that the hanger will be permanently attached to the bed bottom and will always be in the right position to be drawn out for use to any extent desired or may be readily withdrawn or housed so as to have no part projecting beyond the rectangular frame work of the bed bottom and also so as to have no part projecting upwardly or downwardly beyond the thickness of the bed bottom frame.

Further purposes and objects of the invention will appear from the specification and claims herein.

Fig. 1 is a vertical cross section through one edge of a spring bed, embodying my invention, with the lower portion of a coiled spring shown in dotted lines, the section being taken on line 1—1 of Fig. 2.

Fig. 2 is a top view of the parts shown in Fig. 1 without the coiled spring.

Fig. 3 is a vertical sectional view through the edge bar of the bed bottom and through the hanger and attached parts, showing the hanger in housed position; the section being taken on line 3—3 of Fig. 2.

Referring to the drawing in a more par-

ticular description, it will be seen that the construction consists of an angle iron edge bar 8 of the spring bed bottom carrying the usual coiled springs 9 in any desired manner, said edge bar 8 being either the end bars or side bars of said bed bottom.

My invention is particularly adapted to be used with a bed bottom having its edge bar 8 formed of angle iron with its horizontal flange 10 at the top and extending outwardly from the vertical flange 11 and this form of edge bar is contemplated in the complete and preferred embodiment of my invention; but it will be understood that my invention is not limited to this precise form of edge bar.

At each point in the edge bar 8 where it is desired to have an adjustable hanger, there is provided an aperture 12 extending through the upper part of the vertical flange 11 in a horizontal direction, with its upper edge on a level with or close to the level of the lower surface of the horizontal flange 10 of the edge bar as is particularly shown in Fig. 3. This aperture 12 is of such height and width as to allow the shank or main flat portion 13 of the L-shaped hanger 14 to readily slide through said aperture.

The hanger 14 is formed of a piece of strong rigid metal, having its main portion 13 arranged horizontally and having at its outer end a down-turned portion or ear 15, so that the hanger in side elevation has the appearance of an L with a very short base, which is the ear 15.

Just below the inner end of the hanger 14 there is provided and secured a bracket 16 conveniently formed of a short piece of angle iron having its vertical flange resting against the inner face of the vertical flange 11 of the edge bar of the bed bottom and rigidly and permanently fastened thereto, as by a pair of rivets 17. The horizontal flange or portion of this bracket has rigidly attached thereto and extending upwardly therefrom a headed pin 18. The shank of this pin loosely fits an elongated slot 19, provided in the inner portion of the hanger 14 and extending longitudinally thereof from near its inner end to a point about half way or a little more than half way to the outer end of the hanger.

It will now be seen that the hanger construction may have its hanger extended outwardly to the desired extent within the

range of its movement as shown in Fig. 1, so that the outer portion of the hanger will rest upon the side rail 20 of the bedstead, with the ear 15 at the outer end of the 5 hanger engaging the outer side or corner of said side rail to prevent accidental displacement of the hanger inwardly of the side rail. With the parts in this position, the 10 weight of the bed bottom is carried by the hangers by the upper surface of the hanger engaging the lower surface of the horizontal flange 10 of the edge bar 8 with an upwardly directed tension and with the lower 15 surface of the inner end of the hanger engag- 15 ing the bracket 16 with a downwardly directed tension. It will be seen that the bracket is of such relative size, location and strength as to well take this strain. It will be noted particularly that none of the 20 strain of carrying the weight of the bed bottom is placed upon the headed pin 18. The function of the headed pin is to limit the movement of the hanger in an outwardly direction when in use and to limit the in- 25 ward or outward movement of the hanger when not in use. In other words the headed pin 18 retains the hanger permanently upon the edge bar; but allows it to be withdrawn or housed as occasion requires. The pin 30 also aids in causing the hanger when ex- 35 tended to be substantially at right angles to the edge bar 8.

It will be noted that the hanger is not limited in use to an angle iron side rail; but may be used with any form of side rail

and may be used with an angle bar side rail in any relative arrangement of its flanges.

What I claim as new and desire to secure by Letters Patent is:

1. In an adjustable bed hanger construction, the combination of a bed bottom angle-iron edge bar having its horizontal flange at the top and extending outwardly with an aperture through the upper part of the vertical flange of said edge bar, an inwardly extending bracket on the inner side of said vertical flange immediately below said aperture, an upwardly extending headed pin on said bracket, a hanger slidingly mounted intermediate its ends in said aperture and having at its inner portion a longitudinally extending slot through which extends the shank of said pin and a downwardly extending hook at the outer end of said hanger. 40 45 50 55
2. In an adjustable bed hanger construction, the combination of a bed bottom edge bar having an aperture therethrough and an inwardly extending bracket on the inner side of said bar immediately below said aperture, an upwardly extending headed pin on said bracket, a hanger slidingly mounted intermediate its ends in said aperture and having at its inner portion a longitudinally extending slot through which extends the shank of said pin and a downwardly ex- 60 65 tending hook at the outer end of said hanger. 60

In witness whereof I have affixed my signature, this 31st day of August, 1923.

WILLIAM B. FOSTER.
